UNITED STATES PATENT OFFICE.

DAVID RENSHAW, OF COHASSET, ASSIGNOR OF ONE-HALF TO HARVEY T. LITCHFIELD, OF HULL, MASSACHUSETTS.

UTILIZING EXHAUST-STEAM.

SPECIFICATION forming part of Letters Patent No. 244,669, dated July 19, 1881.

Application filed October 14, 1880. (No model.)

To all whom it may concern:

Be it known that I, DAVID RENSHAW, of Cohasset, in the county of Norfolk and State of Massachusetts, have invented a new and useful Improvement in Utilizing Exhaust-Steam; and I do hereby declare that the following is a full, clear, and exact description of the invention, which will enable others skilled in the art to make and use the same.

10 My invention consists in a process by means of which exhaust-steam can be returned to the boiler from which it emanated; and, further, in a device to assist said process. The process consists in taking steam from the boiler to a 15 pump or equivalent device, then forcing said steam to a superheater, and then passing the superheated steam through an injecting device, into which the exhaust-steam enters in such a manner that the superheated steam will take 20 up the exhaust-steam and throw it back to the boiler.

In the drawings, I have shown a boiler, A; an engine, E; a pump, B, worked by the boiler, drawing steam from the boiler and forcing it 25 to a superheater, C; and an injecting device, D, connected with the superheater, the exhaust-steam pipes *d* from the engine and pump, and with the boiler.

A', A², and A³ show the pipes supplying 30 steam to the engine and pump, and A⁴ shows the pipe from the pump to the superheater.

Figures 1 and 2 show the general arrangement of the boiler, engine, pump, superheater, and injecting device; and Fig. 3 shows said 35 device in detail.

The elements of this process consist in supplying the superheater with steam which can only act in one way upon the boiler, its backward pressure or "kick" being overcome by 40 the check-valves of the pump, the pump acting on the boiler-steam as an air-pump acts on air.

It is well known that when a boiler is connected with a superheater in the usual manner the pressure throughout the whole contents of the boiler and superheater is equal; and it is also well known that steam at a high 45 pressure may be put into a boiler containing steam at a low pressure until both boilers have the same pressure. It is also well known that

an air-pump will pump air into a vessel to an 50 almost indefinite extent of pressure.

This part of my invention is simply an air-pump applied to steam, the piston for the working steam being larger than that for the steam to be pumped to the superheater, and 55 its pumping force being regulated by the variation in the diameters of said pistons. When the boiler-steam thus compressed by the pump into the chamber of the superheater is superheated, its pressure is increased, and it tends 60 to force its way to the boiler with great velocity, and if not prevented by any check-valves it will take up the steam which is thrown off as exhaust, raise its temperature and force it back to the boiler, the velocity and heat attained by said pumped and superheated steam being relied on for that purpose.

The pump B, which I have shown in the drawings, is a fly-wheel pump consisting of a pumping-engine, m, and a pump proper, n, fitted with the requisite valves, and having pistons connected by a piston-rod, p, the stroke of the pistons being controlled by the connecting-rod s, which extends from the piston-rod to the crank-shaft of the fly-wheel r.

The injecting device which I consider best for conducting the steam from the superheater to the boiler is shown in the drawings. It consists, mainly, of a frusto-conical chamber, a, from the apex of which a pipe, b, connects 70 with the boiler, the pipe having a cock, c, to open or close, as required. Near the apex the exhaust-steam pipe *d* enters the chamber, and opposite a pipe, e, leads from the chamber to conduct the exhaust-steam away, this latter 75 pipe being fitted with a cock, f, acting in opposition to the cock leading from the boiler, both being operated by one handle, x, so that when one is closed the other is open. The superheated steam enters a chamber, h, in the 80 rear of the conical chamber a, and passes to a tube, i, (through openings k,) which extends to near the apex of said conical chamber, its distance from the apex being made adjustable, as shown.

When the exhaust is to be passed away it is sent through the chamber a, entering the chamber through the pipe *d*, and passing from

it through the pipe *e*, the cock *e* in this instance being closed and the cock *f* opened, both of these cocks being so constructed that when open there can be no obstruction to the 5 body of steam passing through them.

When it is desired to force the exhaust to the boiler the superheated steam is passed through the tube *i* to the chamber *a*, and the 10 cocks *e* and *f* being reversed, a free passage is opened for the steam from the superheater to drive the exhaust-steam back to the boiler, no obstruction in the way of check-valves or their equivalents being interposed.

I do not claim any particular boiler, super- 15 heater, or injecting device in connection with this process; but

I claim as my invention, and desire to secure by Letters Patent—

1. The process for driving the exhaust-steam back to the boiler, consisting of pumping steam 20 from a boiler into a superheater, there superheating said steam, and then using it to drive exhaust-steam back to the boiler through an injecting device, substantially as described.

2. In connection with a superheater sup- 25 plied with steam from a pump, as described, the injecting device *D*, consisting of a cham- 30 ber, *a*, with entrance-pipe *i* for the superheated steam, entrance-pipe *d*, and outlet-pipe *e* for the exhaust, and pipe *b* connecting said cham- 30 ber *a* with the boiler, all as described and for the purpose specified.

DAVID RENSHAW.
